(57) **CLAIM**

The ornamental design for a shoe body, as shown and described.

DESCRIPTION

FIG. 1 is a front perspective view of a shoe body;
FIG. 2 is a top plan view of the shoe body shown in FIG. 1;
FIG. 3 is a bottom plan view thereof;
FIG. 4 is a front elevational view thereof;
FIG. 5 is a rear elevational view thereof;
FIG. 6 is a left side elevational view thereof; and,
FIG. 7 is a right side elevational view thereof, with a toy head
for use with the shoe body shown in broken lines.

The ornamental design which is claimed is shown in solid lines in the drawings. Any broken lines in the drawings are for illustrative purposes only and form no part of the claimed design.
